US00D714147S

(12) **United States Design Patent**
Lindstrom, Sr.

(10) **Patent No.:** **US D714,147 S**
(45) **Date of Patent:** **** Sep. 30, 2014**

(54) **CAP FOR A CONTAINER**

(75) Inventor: **Erik J. Lindstrom, Sr.**, Denver, CO (US)

(73) Assignee: **Schwoggle, Ltd.**, Denver, CO (US)

(**) Term: **14 Years**

(21) Appl. No.: **29/423,737**

(22) Filed: **Jun. 4, 2012**

(51) **LOC (10) Cl.** **09-07**

(52) **U.S. Cl.**

USPC **D9/453**

(57) **CLAIM**

The ornamental design for a cap for a container, as shown and described.

DESCRIPTION

FIG. 1 is a top perspective view of a cap for a container;

FIG. 2 is a bottom perspective view of FIG. 1;

FIG. 3 is a front view of FIG. 1;

FIG. 4 is a rear view of FIG. 1;

FIG. 5 is a top view of FIG. 1;

FIG. 6 is a bottom view of FIG. 1;

FIG. 7 is a right side view of FIG. 1; and,

FIG. 8 is a left side view of FIG. 1.

1 Claim, 4 Drawing Sheets
